(57) **CLAIM**

The ornamental design for a projector, as shown and described.

DESCRIPTION

FIG. 1 is a front, right side, top perspective view of a projector showing our new design;

FIG. 2 is a front, left side, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a reference perspective view 1 thereof, showing a state in which a cover part is detached;

FIG. 10 is a reference perspective view 2 thereof, showing a state in which the cover part is detached;

FIG. 11 is a reference front elevational view thereof, showing a state in which the cover part is detached; and,

FIG. 12 is a reference rear elevational view thereof, showing a state in which the cover part is detached.

The portions in broken lines are shown for illustrative purposes only and form no part of the claimed design.
